UNITED STATES PATENT OFFICE

151,513

DESIGN FOR A COMBINED CIGAR, CIGARETTE, AND MATCH HOLDER

Fred J. Hayman, Forest Hills, N. Y.

Application October 28, 1946, Serial No. 134,342

Term of patent 3½ years

(Cl. D85—2)

To all whom it may concern:

Be it known that I, Fred J. Hayman, a citizen of the United States, residing at Forest Hills, in the county of Queens and State of New York, have invented a new, original, and ornamental Design for a Combined Cigar, Cigarette, and Match Holder, of which the following is a specification, reference being had to the accompanying drawing, forming a part thereof.

Fig. 1 is a front elevational view of a combined cigar, cigarette, and match holder, showing my new design.

Fig. 2 is a vertical sectional view taken on line 2—2 of Fig. 1.

Fig. 3 is a vertical sectional view taken on line 3—3 of Fig. 2.

Fig. 4 is a partial top plan view of a combined cigar, cigarette, and match holder, as seen in the direction of the arrows 4—4 of Fig. 1.

Fig. 5 is a perspective view from one end and looking down at the combined cigar, cigarette, and match holder shown in Figs. 1—4 inclusive.

I claim:

The ornamental design for a combined cigar, cigarette, and match holder, substantially as shown.

FRED J. HAYMAN.
